UNITED STATES PATENT OFFICE.

DANIEL WILLIS ARAVE, OF POCATELLO, IDAHO.

WEATHER-STRIP GUIDE.

Application filed May 23, 1923. Serial No. 640,952.

To all whom it may concern:

Be it known that I, DANIEL W. ARAVE, a citizen of the United States, and resident of Pocatello, in the county of Bannock and State of Idaho, have invented certain new and useful Improvements in Weather-Strip Guides, of which the following is a specification.

My invention relates to improvements in weather strips of that type of construction in which cooperative metallic members are provided on the sash or like sliding closure and on the frame therefor, and it consists in the combinations, constructions and arrangements herein described and claimed.

An object of the invention is to provide a novel attachment of the character described which comprises metallic slide members on opposite members of a window sash or like sliding closure in sliding engagement with metallic guide means on the frame or casing for the sash or other closure, whereby the window sash or like closure will be mounted to slide easily at all times, the sash and the frame being braced by the cooperative elements of the attachment and being protected against the action of the elements and against the entrance of dust, cinders and the like between the relatively moving contiguous surfaces of the sash or like closure and the frame therefor.

Other objects and advantages will be apparent from the following description, considered in conjunction with the accompanying drawings, in which—

Figure 1 is a side elevation of a portion of a locomotive engine cab, showing the windows thereof, equipped with a practical embodiment of the invention,

Figure 2 is a transverse vertical section through the window frame and through the sashes therein, certain of the latter being shown in open position or juxtaposed relation,

Figure 3 is a fragmentary perspective view showing a portion of the top member of one of the sashes shown in the preceding views, and

Figure 4 is a view similar to Figure 3 showing a portion of the sill or bottom member of the frame shown in Figures 1 and 2.

As is well known the window construction of a locomotive engine cab ordinarily comprises a frame and one or more horizontally sliding sashes arranged to work in grooves

in the sill or bottom member and in the top member of the frame. In actual practice, cinders, dust, snow, rain and the like enter between the contiguous sliding surfaces of the windows and the frame therefor and preclude ease of operation of the windows while also tending to cause wear on the contiguous relatively moving surfaces of the window and frame and sagging and distortion of the sash and frame members, thereby rendering the window unserviceable in time.

The objectionable features of a sliding window or closure of the type of construction just described are obviated when the sliding window or closure and the frame therefor are equipped with a practical embodiment of the invention. Such an embodiment of the invention includes narrow plates or strips 1 and 2 respectively made of a light gauge metal and disposed in flatwise contiguous relation to the outer faces of the upper frame member 3 and the sill 4 respectively, as best seen in Figure 2. The plates 1 and 2 constitute spacing members and respectively extend above the upper side of the top frame member 3 and below the lower side of the sill 4. The portion of the plate 1 extending above the top member 3 is secured by means of bolts 5 or like fastening elements to the vertical side of an angular metallic member 6, the horizontal side of which is disposed upon the upper side of the top member 3 and is secured to the latter by means of bolts 7 which extend vertically through the top member 3.

In like manner, the plate 2 is secured by rivets 8 to the vertical side of an angular metallic member 9, the horizontal side of which is arranged in flatwise contiguous relation to the under side of the sill 4 and is secured to the latter by means of bolts 10 which extend through the sill. The bolts 7 and 10 have the heads thereof countersunk in the frame members through which they extend.

The inner faces of the top frame member 3 and of the sill 4 are reinforced by inner facing plates 11 and 12 respectively which at their remote longitudinal edges abut the inner faces of extending portions of the horizontal sides of the angular members 6 and 9 respectively and which extend inwardly or in other words toward each other beyond the planes of the proximate sides of the top member 3 and the sill 4. The

plates 11 and 12 are made of a light gauge metal and are secured to the frame members with which they are associated by means of screws 13.

5 With the arrangement described so far the top frame member 3 and the sill 4 and consequently the entire window frame will be effectually braced against warping and distortion because of the action of the 10 weather thereon or for like cause.

In the embodiment of the invention illustrated, the window 14 is stationary and is positioned at one end of the window frame. The frame is shown as being mounted in a 15 suitable opening in the side of a locomotive engine cab which is designated generally at 15. The windows 16 and 17 are slidable horizontally from closed position, as illustrated in Figure 1, to open position in which 20 they are disposed substantially in register with the stationary window 14, as shown in the drawing. The window 16 which is the middle window of the series has the inner and the upper faces of the top member 25 thereof covered by an angle member 18. The inner and lower faces of the bottom member of the middle window 16 are covered by an angle member 19. The angular member 18 has a vertically disposed side arranged in 30 flatwise contiguous relation to the inner face of the top member of the sash of the window 16 and is secured to the latter by means of screws 20 so that the horizontally disposed side of the angle member will rest upon 35 the upper face of the top member of the window sash and the outer face of an upturned longitudinal extension 21 at the outer edge of the horizontal portion of the angle member 18 will lie in the plane of the outer 40 face of the sash of the window 16. The horizontal portion of the angle member 18 has an elongated portion struck-up therefrom as indicated at 22, the struck-up portion extending in spaced parallel relation 45 to the extension 21 and terminating at its upper edge in the plane of the upper edge of the extension 21. The extension 21 and the struck up portion 22 constitute guiding and retaining elements for engaging with 50 the opposite sides of a depending portion of an angular rail 23 which is secured to the lower face of the top frame member 3 and with which the horizontal portion of the angle member 18 is in sliding contact.

55 The angle member 19 which is applied to the bottom member of the sash of the window 16 is identical in essential respects with the angle member 18 and is provided along its outer edge with a depending extension 60 21' and with a downwardly struck portion 22' in spaced parallel relation to the extension 21', the extension 21' and the downwardly struck portion 22' constituting guiding and retaining elements in engagement 65 with the opposite sides of the upstanding

vertical portion of a rail 23' which is identical in construction with the rail 23 and is secured upon the upper face of the sill 4. The arrangement is such that the vertical portions of the rails 23 and 23' lie in the same vertical plane and the vertical portions of such rails are provided at their ends remote from the stationary window 14 with laterally turned portions such as indicated at 24 which constitute stops for limiting the 70 sliding movement of the window 16 toward the end of the frame opposite to that provided with the stationary window 14. The inner face and the upper face of the top member of the sash of the window 17 are 75 covered and reinforced by an angle member which is precisely identical in essential respects with the angle member 18 and which therefore has been indicated by the same reference numeral. The horizontal portion of the angle member 18 which is applied to the upper or top member of the sash of the window 17 is provided with the upstanding marginal extension 21 and the struck up portion 22 in spaced parallel relation thereto, the extension 21 and the struck up portion 22 of the last mentioned angle member 18 being in sliding engagement with the opposite faces of the depending portion of the plate 11 which has been hereinbefore described, such depending portion of the plate 11 being indicated at 25 and constituting a rail with which the horizontal portion of the last mentioned angle member 18 is in 80 sliding contact. Similarly, the bottom member of the sash of the window 17 is provided with one of the angle members 19 and the depending extension 21' and the downwardly struck portion 22' of the latter are in 85 sliding engagement with the opposite faces of the upstanding portion of the plate 12, which upstanding portion is designated 26 and constitutes a rail which lies in the vertical plane of the plate 11 and relatively to 90 which the last mentioned angle member 19 is in 95 sliding contact. It thus will be apparent that the vertically aligned angle members 18 and 19 which are secured to opposite members of the sash of each of the sliding windows 100 comprise a pair of wear resisting slide shoes which engage with a pair of vertically aligned horizontal rails carried by opposite members of the window frame in such manner that the sliding window is held against 105 bodily movement laterally of its general plane but is permitted to slide freely and easily in its general plane between limits established by one end of the window frame and by either the stops 24 on the rails 23, 23' or similar stops 24' at one end of the 110 rails 25, 26. The angle members 18 and 19 brace the members of the window sashes to 115 which they are applied and particularly protect the inner edge portions of such members of the window sashes. The relatively 120

moving portions of the window sashes and thereof which fairly fall within the scope 25
the window frame are covered by metallic of the appended claim.
members having good wear resisting prop-
erties.

5 The portions of the sashes which slide on
the frame members do not enter grooves in
the latter but are mounted to slide on rails
carried by the frame members and therefore
the windows are not likely to "stick" when
10 subjected to the action of the elements, par-
ticularly moisture.

While I have shown a practical embodiment
of the invention as being applied to
sliding windows of a locomotive engine cab,
15 it will be obvious that the invention is ap-
plicable to sliding windows of various types
of construction without departing from the
spirit and scope of the invention. Also
many modifications of the form of the de-
20 vice disclosed in the foregoing and illustrated
in the drawings may be provided with-
out departing from the spirit and scope of
the invention and I therefore consider as
my own all modifications and adaptations

Having thus described the invention, what
I claim is:—

The combination with a sliding closure
and the frame therefor, of a pair of metallic 30
rails extending inwardly of the inner faces
of two parallel members of the frame, and
longitudinal metallic slide members secured
to the closure and having portions upon
35 the faces of the closure which are in con-
fronting relation to said faces of the frame
members, said portions of the slide mem-
bers being in sliding contact with the inner
faces of the rails and each slide member also
40 having spaced guiding and retaining por-
tions in sliding engagement with opposite
lateral faces of one of said rails, each of
said rails being provided at one end thereof
with a laterally turned end portion extend-
45 ing in the path of movement of the slide
member with which said rail is associated.

DANIEL WILLIS ARAVE.
